ARRANGEMENT FOR CHANGING OVER THE
SPEAKING DIRECTION IN LOUD-SPEAKER
DUPLEX SYSTEMSOtto Tschumi, Soleure, Switzerland, assignor to
Autophon Aktiengesellschaft, Soleure, Switzerland, a joint-stock company of SwitzerlandApplication May 12, 1944, Serial No. 535,297
In Switzerland December 4, 1942

1 Claim. (Cl. 179—1)

1

The invention relates to arrangements for changing over the speaking direction in loud speaker duplex systems.

The determination of the speaking direction in loud speaker duplex systems was hitherto effected by an additional key which, in most cases, was adjoined to the station establishing the connection and which remained in operating position as long as a certain speaking direction was desired. The changing-over of the speaking direction was carried out by letting the key go.

The great disadvantage of this device consists in the fact that this changing-over could be effected in one station only so that in this station alone it was possible to change the speaking direction. The subordination of the stations resulting therefrom was unsuitable for many purposes and it was, therefore, desired to create a changing-over arrangement guaranteeing a complete coordination of the subscriber's stations.

Object of the present invention is an arrangement for changing-over loud speaker duplex systems which is characterized in that the changing-over is effected by a short-time change of an electric continuous state. This state may be of any kind, that is, it may consist in the fact that a more or less intense current flows through the switch devices, or that the latter are without current. Therefore the short-time change of the electric continuous state consists in a current amplification, a current reduction, a current impulse or an interruption.

The means by which the changes can be effected are various and are well-known to those skilled in the art.

The accompanying drawings illustrate, by way of example, one embodiment of the object of invention.

Fig. 1 is a diagram of the subscriber's device, while

Figs. 2 to 4 illustrate in a diagrammatic way details of the main station.

For effecting a short-time change in the electrical connections, the subscriber desiring to change the speaking direction in the example illustrated dials the number 1 on the existing calling dial, i. e., he interrupts a direct current for a short time. This use of the calling dial has the additional advantage that no further switching devices need be added to the subscriber's station in that the existing means are sufficient.

Referring now to Fig. 1, the transducer EW is connected with the terminals *a*, *b* over the amplifier V which can be alternately switched-in

2

by the switches *u*₁ and *u*₂. The terminals *a* and *b* are connected with each other by the impedance coil Dr. The centre of this coil Dr is earthed over the switch *e*₂, a rectifier arrangement with the relays U, E and the optical signal SZ, and over the impulse contact *i* of the calling dial NS.

In Fig. 2 *a*, *b*₁ are the connections for the calling and *a*₂, *b*₂ the connections for the called subscriber's station. The centres of the transformer windings, both on the side of the called and on the side of the calling subscriber, are connected over relay J, switch *s*₁ or over relay Y, switch *s*₂ respectively with the negative pole of a non-illustrated battery earthed on the positive side or the positive pole of a non-illustrated battery earthed on the negative side respectively.

Fig. 3 illustrates the arrangement of a relay controlling the switches *s*₁, *s*₂ and *s*₃. This relay is, on the one side, connected to the negative pole of a battery earthed on the positive side, and, on the other side, earthed over the switch II and the switches *y*₁ and *j*₁ connected in parallel.

Fig. 4 shows the circuit of the time-delay relay II controlled by the switches *y*₂ and *j*₂ connected in series.

When the calling subscriber has established a connection with the called subscriber over a connection established by an automatic exchange, the contacts *e*₁ and *e*₂ have been closed in a non-illustrated manner, which, on the one side, results in the switching-in of the amplifier V and, on the other side, in the opening of a direct current path from the middle of the impedance coil Dr over the rectifier arrangement to the earthed contact of the impulse contact *i*. The terminals *a*, *b* in Fig. 1 are connected over pre-selectors or call finders or other selectors with the terminals *a*₂, *b*₂ in Fig. 2 and the terminals of the non-illustrated called station. The establishment of these operating conditions results in the following direct current: earth-impulse contact *i*—rectifier arrangement and relays E and U—*e*₂—impedance coil Dr—terminals *a*, *b*—terminals *a*₁, *b*₁—relay J—contact *s*₁—negative pole of a battery earthed on the positive side. The result is that, on the one hand, relay E continues in action, i. e., the contacts *e*₁ and *e*₂ remain closed and that, on the other hand, relay U also comes into action. Thereby, the switches *u*₁ and *u*₂ are actuated, and the calling station is connected for hearing. On the opposite side (the called station) a similar direct current circuit, but in reversed direction, is formed, so that, contrary to the first-named circuit, relay U is now short-circuited by a rectifier element and, for this

reason, remains without current, while, in its place, the optical signal SZ is inserted into the circuit and flashes up, indicating in this way that this station is in speaking condition.

Now the speaking direction can at will be changed by the calling or the called party by dialling the number 1 on the calling dial. If it is, for instance, the person calling who actuates the dial in the manner aforesaid, the impulse contact is interrupted for a short time and the sparking contact *k* short-circuited during the selecting process. The short-time interruption of the current in the previously mentioned circuit of the calling station does not result in a dropping of the relays U and E which is delayed by the parallel connection of rectifier elements, but only in a dropping of relay J. This dropping closes the circuit of the switch relay S in Fig. 3 which, in its turn, operates the contacts *s*₁, *s*₂ and *s*₃. By the operation of the contacts *s*₁ and *s*₂, the centres of the transformer Tr are connected to the positive pole of a power source earthed on the negative side, and to the negative pole of a power source earthed on the positive side. This results in the formation of the following circuit on the calling station: plus—*s*₁—relay J—terminals *a*₁, *b*₁—terminals *a*, *b*—impedance coil Dr—contact *e*₂—rectifier arrangement—optical sign SZ and relay E—impulse contact *i* and earth. The relay U short-circuited by a rectifier element, and its switches *u*₁, *u*₂, drop and the subscriber's device illustrated is again changed-over for use in speaking such condition being indicated by a flashing-up of the optical signal SZ.

The reverse takes place on the side of the station called which, in its turn, is now changed-over to the hearing position.

The conversation being terminated, the contact *s*₃ serves the purpose of bringing the relay

S back into initial position provided that this is not already the case.

What I claim is:

In a loud speaker duplex system comprising several subscribers stations, an arrangement for changing over the speaking direction including a transducer and a dial in each of said subscriber's stations, dial contacts operated by the dial, a relay arrangement, a battery, contacts for connecting a subscriber station, contacts for changing over the speaking direction, a rectifier arrangement, a bridge relay in said rectifier arrangement operating said contacts for connecting a subscriber station, a shunt relay shunting a part of said rectifier arrangement and operating said contacts for changing over the speaking direction, the whole rectifier arrangement being connected in series, on one hand, with firstly one of said dial contacts, and on the other hand with one of said contacts for inserting a subscriber station, said relay arrangement being also connected alternately to the two poles of said battery.
